UNITED STATES PATENT OFFICE.

FRIEDRICH W. LEHNERT, OF NEW HAVEN, CONNECTICUT.

SOAP MAGAZINE FOR WASHBOARDS.

Application filed July 29, 1921. Serial No. 488,369.

To all whom it may concern:

Be it known that FRIEDRICH W. LEHNERT, a citizen of the United States of America, residing at New Haven, in the county of 5 New Haven and State of Connecticut, has invented new and useful Improvements in Soap Magazines for Washboards, of which the following is a specification.

The object of the invention is to provide a simple and efficient means for supporting and holding bar soap in position to be readily accessible in the rubbing of clothes upon a washboard surface under conditions tending to economize in the use 10 of the soap by preventing the excessive moistening and softening thereof and to provide means for connection therewith whereby the exposed surface of the bar may be adjusted to maintain the same in operative 15 relation with the rubbing surface of the board as the soap is used or worn away by the contact of the fabrics therewith; and also to provide simple and efficient means whereby the magazine provided for the reception 20 of the soap bar may readily be recharged; and with these objects in view the invention consists in a construction and combination of parts of which a preferred embodiment is shown in the accompanying 25 drawings, wherein:

Figure 1 is a front view, and

Figure 2 is a side view of a washboard constructed in accordance with the invention.

Figure 3 is a vertical sectional view of the same.

Figure 4 is a transverse section on the plane of the guide rods and feed screws.

The washboard 10 may in general features 40 be of the ordinary construction having the rubbing surface 11 above which is arranged a transverse slot constituting a feed opening of a length equal to the width of the rubbing surface of the wash board and of a width 45 corresponding approximately with the bar or sectional bars 12 of soap ordinarily used in connection with laundry operations, said feed slot being in communication with the magazine 13 projecting rearwardly from the 50 plane of the washboard frame and contain-

ing a plunger 14 preferably spring actuated as indicated at 15 to effect the advance of the soap as the surface or exposed portion thereof is used.

It is designed that the soap bars shall be 55 held in such a way as to be arranged with their exposed surfaces substantially in the plane of the rubbing surface of the board, and therefore to limit the forward movement of the bars the outlet or mouth of the 60 magazine communicating with the slot in the face of the board is contracted vertically by providing the same with forwardly convergent upper and lower walls 16 which in the plane of the slot or opening are spaced 65 at an interval somewhat less than the width of the soap bars, and in applying the soap bars which may be introduced into the magazine through an end opening normally closed by a hinged cover 17 fitted with a latch 18, 70 the forward edges of the bars are preferably reduced or tapered by shaving the small portion of the surfaces thereof to give the bars near their forward surfaces a somewhat tapered cross-sectional contour as indicated 75 in Figure 3.

Extending rearwardly from the follower are the feed screws 19 and guide rods 20 extending through suitable openings in the rear wall of the magazine, the feed 80 screws being engaged by thumb nuts 21 so as to limit the tendency of the springs to advance the plunger and thus unnecessarily expose the forward surfaces of the soap bars. Obviously by gradually unscrewing 85 the feed nuts the plunger may be permitted to advance to compensate for the waste or use of the soap at its front surface.

It will also be understood that a single bar of soap of a length corresponding with the 90 feed opening may be employed, where the soap is received by the consumer in sufficient lengths to provide for that use although a plurality of bars of the ordinary commercial size may be introduced as indicated in the drawing to occupy the full 95 length of the feed slot or opening.

Having described the invention, what is claimed as new and useful is:—

A washboard having a transverse soap 100

receiving slot raised above its rubbing surface, a magazine carried by the washboard in communication with said slot or opening and adapted to contain soap bars for 5 exposure at their front surfaces in said slot or opening, and means for advancing the soap bars as the front surfaces thereof are removed by use, the upper and lower walls of the magazine being disposed in a forwardly convergent relation to graduate the forward feeding movement of the soap.

In testimony whereof he affixes his signature.

FRIEDRICH W. LEHNERT.
